UNITED STATES PATENT OFFICE.

MAX JACOB, OF BERLIN, GERMANY, ASSIGNOR TO THE NATIONAL CASH REGISTER COMPANY, OF DAYTON, OHIO, A CORPORATION OF OHIO, (INCORPORATED IN 1906.)

TURN-TO-ZERO MECHANISM FOR CASH-REGISTERS.

1,183,010.

Specification of Letters Patent.

Patented May 16, 1916.

Application filed June 18, 1913. Serial No. 774,300.

To all whom it may concern:

Be it known that I, MAX JACOB, a subject of the Emperor of Germany, residing at Berlin, Germany, in the Kingdom of Prussia and Empire of Germany, have invented 5 certain new and useful Improvements in Turn-to-Zero Mechanism for Cash-Registers, of which I declare the following to be a full, clear, and exact description.

10 This invention relates to accounting machines and more particularly to the mechanism for turning the totalizer to zero.

The principal object of this invention is to provide means by which the totalizer may 15 be turned to zero and an item entered thereon during a single regular operation of the machine. To this end a special key is provided which, when operated, couples the turn to zero mechanism to the operating 20 mechanism. Suitable pawls intermediate the totalizer wheels and the shaft supporting the wheels are engaged by a groove in the shaft when rotated to pick up the pawls in whatever position they may stand to turn 25 the wheels to zero during the first part of the operation of the machine. This turn to zero mechanism is constructed to be operated before the differential mechanism of the machine is actuated so that the amount 30 set up on the keyboard may be added on the totalizer during the latter part of the operation of the machine.

With these and incidental objects in view, 35 the invention consists in certain novel features of construction and combinations of parts, the essential elements of which are set forth in appended claims, and a preferred form of embodiment of which is hereinafter described with reference to the drawings 40 which accompany and form part of the specification.

Figure 1 is an end elevation of the register showing the invention applied thereto. Fig. 2 is a transverse vertical section taken 45 along a bank of amount keys and showing the differential mechanism of a register of a type to which the present improvements are shown as applied. Fig. 3 is a top plan view of the turn to zero mechanism shown 50 in Fig. 1. Figs. 4 and 5 are details respectively of the devices employed to aline the totalizer shaft in zero position and to aline the totalizer pinions in their various positions.

55 For convenience of illustration the inven-

tion has been shown as applied to a machine of the type shown and described in Letters Patent of the United States, No. 580,378, issued April 13, 1897 to J. P. Cleal and F. A. Reinhard.

60 The operation of the machine to which the present improvements are shown as applied, is substantially the same as that of the machine shown in the above mentioned Letters Patent, but for the sake of convenience it 65 will be briefly described as follows: The machine comprises a plurality of banks of keys, any one of which keys, when depressed, serves as a stop for a differentially movable rocking segment 2 (Fig. 2). Only one of 70 such banks of keys 1 is shown in the drawings, but it will be understood that the several banks which generally comprise a single machine for practical use are the same in principle and duplicates in construction. 75 Segment 2 receives its rocking movement from a segment 3 to which it is automatically coupled and uncoupled in a manner well known in the art and fully set forth in the above mentioned Letters Patent. Segments 3 are rigidly mounted on the oscillatory shaft 4 which is driven from a main shaft 5 through the medium of an arm (not shown) fast on the shaft 5, pitman 10, and arm 11 rigid on the shaft 4. The main drive 80 shaft 5 is given one complete rotation at every operation of the machine by the crank handle 6 through the gears 7, 8, and 9.

85 Each segment 2 is formed with teeth 12 meshing with similar teeth 13 formed on an intermediate gear 14 through the medium of which gear the differential movement of the segment 2 is transmitted to the indicating and totalizing mechanisms upon the upward movement of the segment 3. The gears 14 mesh with pinions 15 loosely mounted on a shaft 16. Rigidly mounted on the side of each pinion 15 is a smaller pinion 17 (Fig. 2). Immediately beside each pinion 17 is a companion pinion (not shown) rigid with a corresponding totalizing wheel 18 and in order to transmit the differential movement of the pinion 17 to its companion pinion and therefore to the totalizer wheel, there is a broad pinion 19 normally out of mesh with the companion pinions. The broad pinions 19 are carried by arms 21 fast on a rock shaft 22 extending across the machine. The shaft is provided with a depending arm 23 which, at its lower end, is pivoted to a pit- 100

man 24 by a pin 25. The pitman 24 extends rearwardly and is bifurcated at its rear end to straddle the main shaft 5. Carried by the pitman 24 is an anti-friction roller 26 projecting into a groove 27 formed in a box cam 28 rigidly mounted on the main shaft 5. The groove 27 of the box cam 28 is so constructed as to give the pitman 24 one reciprocation at each operation of the machine 10 thus causing the rocking of the shaft 22 and the engagement of the broad pinions 19 with their appropriate pinions 17. This engagement of the pinions 19 with their corresponding pinions 17 is effective only during the time that the segments 2 are receiving their differential adjustment, the totalizing wheels thereby receiving movement to extents commensurate with the value of the keys 1 which were depressed. The intermediate gear 14 constantly meshes with the pinion 31 rigid with the indicating disk 32 so that when the intermediate gear 14 receives its differential movement from the segments 2 the indicators will display the proper amount.

Referring to Figs. 1 and 3, fast on a shaft 33 to which the gear 8 is fastened is a drum 34 having two disks 36 and 37 integral therewith. These disks are of the same diameter and the disk 36 is provided with three teeth 38. The face of the drum carries a circular block or flange 39 which is normally in the path of the inclined edge 41 of a key 42 and the drum is retained in normal outer position when the totalizer is not to be turned to zero by means of a spring 43 coiled about the shaft 33 and the intermediate gear 8 and the disk 37. The key 42 is slidably mounted in brackets 44 and 45 and is normally held in undepressed position by a spring 46 which presses against a pin 47 projecting from the key into a slot 48 in the top of the bracket 45, the other end of the spring being backed by the side of the bracket 45. The drum 34 and the disks 36 and 37 rigid therewith are splined on the shaft 33 so that they have a limited sliding movement lengthwise of the shaft but are given a complete rotation when said shaft is rotated by the driving mechanism. When the turn to zero key 42 is depressed the drum 34 and the disks 36 and 37 are shifted toward the gear 8 and the key is held in its depressed condition with the projection 52 behind the flange 39 on the drum 34 during the initial part of the operation of the machine by the engagement of the projection or shoulder 52 against the inner periphery of the circular flange. 60 By sliding the drum 34 and the disks 36 and 37 toward the gear 8 a block 53 fast on the face of the disk 37 is brought into engagement with one of three pins 54 projecting from the side of the gear 50, and disk 36 is brought into operative alignment with

a mutilated gear 58 rigid with a drum 55 carried by a stub shaft 51 projecting from the side frame of the machine. The gear 50 and its drum 55 at the very beginning of the operation of the machine by the engagement 70 of the block with one of the pins on the gear gives the gear and the drum 55 a slight counter-clockwise movement. This movement of the drum brings the three teeth 38 on the disk 36 into mesh with one of the sets of four teeth 57 on the mutilated gear 58 on the drum 55. There are three sets of teeth 57 on the mutilated gear 58, there being space for one tooth between each set of teeth. 75

From the above description it can readily be seen that the drum 55 and therefore the gear 50 will be given one-third of a rotation upon a complete operation of the machine and that such movement will be imparted during the first 120 degrees of movement of the gear 8. The gear wheel 50 is provided with 36 teeth while a pinion 59, fast on the right hand end of the totalizer shaft 16 and in operative relationship with the gear 50, has but 12 teeth so that when the gear 50 is given 85 its one-third rotation, as described by the clockwise rotation of the crank 6 (Fig. 1), its one-third rotation, as described by the clockwise rotation of the crank 6 (Fig. 1), the totalizer shaft will be given one complete rotation in a clockwise direction to turn the totalizer pinions to zero. 90

The totalizer wheels 18, as stated, are loosely mounted upon the totalizer shaft 16 and these wheels are provided with spring pressed turn to zero pawls 61 (Fig. 5) bearing on the periphery of the shaft. The shaft is provided with a longitudinal groove 62 which is so constructed that when the wheels are turned in a clockwise direction while an item is being entered thereon, the pawls ride idly over the groove. When, however, the shaft is rotated in a clockwise direction the pawls drop into the grooves 62, when the groove is opposite the pawls, and as the pawls are engaged by the radial edge of the groove, rotation of the shaft will 105 therefore carry all the wheels to zero position. 110

The spring pressed arms 63 are employed to align the totalizer wheels in their differentially set position by engaging the notches 115 in star disks 64 rigidly mounted on one side of the totalizer wheels. The pawls 63 are loosely mounted on a shaft 65 but are adapted to be rocked rearward upon oscillation of the shaft as a hub 66 surrounding the shaft and integral with the pawl is provided with diametrically opposite notches 67, one face of each notch being adapted to be engaged by studs 68 projecting from the shaft 65 into the notches. The totalizer shaft 16 carries rigid therewith a disk 69 with a cut out portion 70 positioned thereon to be engaged by a roller 71 carried by an arm 72 fast on the shaft 65. The roller is kept into engagement with the disk by a compressed

spring 73, which tends to rock the arm 72 and therefore the shaft 65 in a counter-clockwise direction. As soon as the shaft 62 begins to rotate the arm 72 and therefore the shaft 65 are rocked rearward and through the engagement of the studs 68 on the shaft 65 with the hubs 66 integral with the alining pawls 63, the pawls are carried out of engagement with the locking disks 64 during about the first 120 degrees of rotation of the drive shaft in a turn to zero operation. At the end of the rotation of the disk 69 the spring 73 restores the shaft 65 and the arm 72 to normal position and the engagement of the roller 71 in the cut out portion 70 aligns the totalizing shaft 16 in its zero position.

The gearing of the machine is so constructed that the rotations of the totalizer wheels to zero position is completed during the first part of the operation of the machine, that is while the segments 3 are being rocked downward. After the totalizer wheels are set to zero and before the upward movement of the segments 21 with the segments 3 the broad pinions 19 are rocked into mesh with the companion pinions 17 so that the differential movement of the segments 2 upon the return movement of the segments 3 will actuate the totalizer wheels 18 to extents commensurate with the value of the amount keys depressed. After the totalizer wheels are set to zero position and before the segments 2 are coupled to the segments 3 for return movement, the circular flange 39 on the face of the drum 34 passes out of engagement with the shoulder 52 on the key and the spring 46 restores the key to normal position. At the same time the spring 43 forces the disks 36 and 37 and the drum 34 to normal position so that continued rotation of these members will not drive the drum 55. The drum 55 is locked from rotation during the last two-thirds of rotation of the drum 34 by the periphery of the disk 37 working in the tooth spaces between the sets of teeth 57 on the gear 58.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

What is claimed is:

1. In an accounting machine, the combination with a totalizer; of operating mechanism therefor; turn to zero devices for the totalizer normally independent of the operating mechanism; and means for preparing the turn to zero devices for operation so that the totalizer may be set to zero and an item entered thereon during the same operation

of the machine that the turn to zero devices are prepared for operation.

2. In an accounting machine, the combination with a totalizer; of differential mechanism therefor; manipulative means for controlling the extent of movement of the differential mechanism; a main operating mechanism; a device for setting the totalizer to zero; and a manipulative means independent of said first manipulative means for coupling said operating mechanism with said turn to zero device so that after the second manipulative means is operated and during the same operation of the machine, the totalizer is turned to zero and an item entered thereon.

3. In an accounting machine, the combination with a totalizer; of means for entering items thereon; connections for resetting the totalizer to zero upon certain operations of the means and before the latter enters an item on the totalizer at the same operation of the machine; and a device for preparing said connections for operation by said means at the same operation of the machine that the totalizer is reset to zero.

4. In an accounting machine, the combination with a totalizer; of means for entering items thereon; connections for resetting the totalizer to zero upon certain operations of said means and before an item is entered on the totalizer at the same operations; and manipulative means for controlling said connections and operable for such purpose at the same operation of the machine that the totalizer is reset to zero.

5. In an accounting machine, the combination with a totalizer; of means for entering items thereon; connections for resetting the former to zero upon certain operations of the latter; and means for locking said resetting connections against movement after the totalizer has been reset to zero and before an item is entered on the totalizer.

6. In an accounting machine, the combination with a main operating mechanism; of differential mechanism driven thereby; a plurality of totalizer elements actuated by said differential mechanism; a single rotatable shaft upon which said totalizer elements are mounted; connections intermediate the shaft and totalizer elements for resetting the latter upon a rotation of the former; and means intermediate the shaft and the main operating mechanism for rotating the shaft before the differential mechanism is actuated by the main operating mechanism to enter an item on the totalizer during the same operation of the main operating mechanism.

7. In an accounting machine, the combination with a main operating mechanism; of a totalizer; differential mechanism for actuating the totalizer and driven by the

operating mechanism; a single rotatable shaft on which said totalizer is mounted; connections intermediate the shaft and the totalizer elements for resetting the latter to zero upon a rotation of the former; adjustable means intermediate the shaft and the main operating mechanism capable of rotating the shaft upon an operation of the main operating mechanism and before the actuation of the totalizer by the differential mechanism; and a manipulative means for rendering said adjustable means operative.

8. In an accounting machine, the combination with a totalizer; of means for entering items thereon; connections rendered operative for setting the totalizer to zero upon the initial movement of the means and at the same operation of the machine; and additional means for rendering said connections ineffective after the totalizer has been restored to zero so that continued operation of said first means enters an item on the totalizer.

9. In an accounting machine, the combination with a totalizer comprising a plurality of movable elements; of a main operating mechanism for driving the same; a resetting shaft on which said elements are loosely mounted; a pinion fast on said shaft; a gear meshing with said pinion; a mutilated pinion rigid with said gear; and a disk given a complete rotation by the operating mechanism and provided with projections for engaging the teeth on said mutilated pinion to turn the resetting shaft upon the initial movement of the main operating mechanism and before an item is entered on the totalizer by the final movement of the operating mechanism.

10. In an accounting machine, the combination with a totalizer comprising a plurality of movable elements and a main operating mechanism for driving the same; of a resetting shaft on which said elements are loosely mounted; a pinion fast on said shaft; a gear meshing with said pinion; a mutilated pinion rigid with said gear and a slideable disk given a complete rotation by the operating mechanism and provided with projections for engaging the teeth on said mutilated pinion and normally out of co-operative relationship therewith; and a manipulative means for moving said disk into co-operative relationship with the mutilated pinions to turn the resetting shaft upon the initial movement of the main operating mechanism and before an item is entered on the totalizer by the final movement of the operating mechanism.

11. In an accounting machine, the combination with a totalizer, comprising a plurality of totalizer elements; of a main operating mechanism for driving the same; a resetting shaft on which totalizer elements are loosely mounted; a pinion fast on said

shaft; a gear meshing with said pinion; a mutilated pinion rigid with said gear; a slideable disk given a complete rotation by the operating mechanism and provided with projections for engaging teeth of the said mutilated pinion but normally out of co-operative relationship therewith; manipulative means for moving said disk into co-operative relationship with the mutilated pinions to turn the resetting shaft on the initial movement of the operating mechanism; and means for automatically moving said disk to normal position before an item is entered on the totalizer by the final movement of the operating mechanism.

12. In an accounting machine, the combination with a totalizer, comprising a plurality of totalizer elements; a main operating mechanism for driving the same; a resetting shaft on which said totalizer elements are loosely mounted; a pinion fast on said shaft; a gear meshing with said pinion; a mutilated pinion rigid with said gear; a slideable disk given a complete rotation by the operating mechanism and provided with projections for engaging teeth of the said mutilated pinion but normally out of co-operative relationship therewith; manipulative means for moving said disk into co-operative relationship with the mutilated pinions to turn the resetting shaft on the initial movement of the operating mechanism; means for automatically moving said disk to normal position before an item is entered on the totalizer by the final movement of the operating mechanism; and a disk co-operating with said mutilated gear for preventing further rotation of the gear after the resetting shaft has been given one complete rotation.

13. In an accounting machine, the combination with an accounting device; of means for entering items thereon; connections for resetting the accounting device to zero upon certain operations of the means and before the latter enters items on the totalizer at the same operations; and alining devices for the accounting device constructed to be withdrawn from alining position while the accounting device is being reset to zero.

14. In an accounting machine, the combination with a totalizer; of means for entering items thereon; connections for resetting the former to zero upon certain operations of the latter and before an item is entered on the totalizer at the same operations; alining devices for alining said totalizer in its various positions and constructed to be withdrawn from alining position while the accounting device is being reset to zero; and manipulative means for controlling said connections.

15. In an accounting machine, the combination with a main operating mechanism; of a totalizer; differential mechanism for actuating the totalizer and driven by the

operating mechanism; a resetting shaft on which said totalizer is mounted; connections intermediate said shaft and the main operating mechanism for rotating the shaft 5 to turn the totalizer to zero upon an operation of the main operating mechanism and before the actuation of the totalizer by the differential mechanism; and alining devices for the totalizer adapted to be withdrawn 10 from alining position while the totalizer is being reset to zero.

16. In an accounting machine, the combination with a main operating mechanism; of a totalizer; differential mechanism for 15 actuating the totalizer driven by the operating mechanism; a resetting shaft on which said totalizer is mounted; connections intermediate said shaft and the main operating mechanism for rotating the shaft to 20 turn the totalizer to zero upon an operation of the main operating mechanism and before the actuation of the totalizer by the differential mechanism; alining pawls normally in engagement with said totalizer for alining 25 the same; and connections intermediate said resetting shaft and the alining pawls to carry the alining pawls out of engagement with the totalizer upon rotation of the shaft.

17. In an accounting machine, the combination with an accounting device; of means for entering items thereon; connections for resetting the former to zero upon certain operations of the latter and before an item 55 is entered on the totalizer; yieldingly mounted pawls for alining the totalizer and in engagement therewith while the totalizer is being actuated; and means actuated by said resetting connections for positively withdrawing said pawls from alining position 40 while the totalizer is being reset to zero.

18. In an accounting machine, the combination with a main operating mechanism; of a totalizer; differential mechanism for 45 actuating the totalizer driven by the operating mechanism; a resetting shaft on which said totalizer is mounted; connections intermediate said shaft and the main operating mechanism for rotating the shaft to turn the 50 totalizer to zero upon an operation of the main operating mechanism and before the actuation of the totalizer by the differential mechanism; and yieldingly mounted alining pawls for the totalizer adapted to be positively withdrawn from alining position only 55 while the totalizer is being reset to zero.

19. In a machine of the class described, the combination with a totalizer, of operating devices therefor, normally ineffective 60 means for clearing the totalizer, and means for rendering the clearing means effective whereby to clear the totalizer and enter an item thereon during the same operation of the machine as said clearing means is rendered effective.

20. In a machine of the class described, the combination with a totalizer, of operating mechanism therefor and means for controlling same, means for clearing the totalizer, manipulative means for rendering the clearing means effective whereby to clear the totalizer and enter an item thereon at the same operation of the machine as said clearing means is rendered effective. 70

21. In a machine of the class described, the combination with a main driving mechanism, of a totalizer, operating devices therefor, means for clearing the totalizer, manipulative means for controlling said operating devices and clearing means adjustable 80 preliminary to an operation of the main driving mechanism whereby to clear the totalizer and then enter an item thereon during said operation.

22. In a machine of the class described, the combination with a totalizer, of actuating devices therefor, manipulative means for predetermining amounts to be entered in the totalizer by the actuating devices, normally ineffective means for clearing the totalizer, 90 adjustable means for rendering the clearing means effective, said adjustable means and the aforesaid manipulative means being simultaneously operable whereby to cause during a single operation the clearing of the totalizer and the entry therein of the amount set up on the manipulative means at the same time that the adjustable means is adjusted.

23. In a machine of the class described, the combination with a totalizer, of actuating devices therefor, a keyboard for controlling said actuating devices, normally ineffective means for clearing the totalizer, a manipulative device for rendering said means effective, the keys of the keyboard and the manipulative device being simultaneously operable whereby to cause during a single operation the clearing of the totalizer as a preliminary to the entry therein of the item set up on the keyboard at the time that said manipulative device is manipulated. 100

24. In a machine of the class described, the combination with a driving mechanism, of a totalizer, means for entering items in the totalizer, means for clearing the totalizer, means operable as a preliminary to an operation of the main driving mechanism whereby to cause both the item entering and 110 the totalizer clearing means to perform their functions during said operation, and means for disabling the clearing means after it has performed its function.

25. In a machine of the class described, the combination with a main driving mechanism, of a totalizer, item entering devices therefor, totalizer clearing devices, manipulative means operable as a preliminary to 125 an operation of the main driving mecha- 130

nism whereby to cause both the item entering and the totalizer clearing devices to perform their functions during said operation, and means for automatically disabling the clearing devices after they have performed their function and preliminary to operation of the item entering mechanism.

In testimony whereof I affix my signature in the presence of two witnesses.

MAX JACOB.
